F. G. TOMPSETT.
ELECTRICAL AMPLIFIER FOR SPARK PLUGS.
APPLICATION FILED JULY 2, 1919.

1,323,503.

Patented Dec. 2, 1919.

Inventor,

Frank G. Tompsett,

Niram A. Sturges,
Attorney.

UNITED STATES PATENT OFFICE.

FRANK G. TOMPSETT, OF OMAHA, NEBRASKA.

ELECTRICAL AMPLIFIER FOR SPARK-PLUGS.

1,323,503.

Specification of Letters Patent. Patented Dec. 2, 1919.

Application filed July 2, 1919, Serial No. 308,230.

To all whom it may concern:

Be it known that I, FRANK G. TOMPSETT, a citizen of the United States, residing at Omaha, in the county of Douglas and State 5 of Nebraska, have invented certain new and useful Improvements in Electrical Amplifiers for Spark-Plugs, of which the following is a specification.

This invention relates to electrical amplifiers, intensifiers or spark-gaps, being an attachment for use in connection with spark-plugs, and has for its object to provide a housing for any required number of electrical amplifiers, the parts to be few and 15 simple so that manufacture will be convenient and economical and that durability may be attained.

The invention consists of the novel construction, combination and arrangement of 20 parts as described herein and claimed, and as illustrated in the accompanying drawing, wherein,—

Figure 1 is a plan view of the device. Fig. 2 is a sectional view on line 2—2 of Fig. 25 1. Fig. 3 is a plan view of the insulating-plate. Fig. 4 is a transverse section through the casing and insulating-plate, on line 4—4 of Fig. 1. Fig. 5 is an end view of the casing showing a brace and a tie-strip before 30 being bent.

Referring now to the drawing for a more particular description, the device consists, in part, of an insulating-plate 6 provided with apertures α near its ends, and having 35 numerous apertures 7 arranged in pairs for receiving eyelets 8, the eyelets of each pair being disposed at approximately uniform distances from each other, the flanges a and b of each eyelet being disposed respectively 40 upon the upper and lower sides of the plate 6.

Disposed in the apertures of the eyelets are screw-bolts 9, and interposed between the keepers 10 and flanges b of the eyelets 45 are electrical conductors, arranged in pairs, the conductors for each pair being indicated at c and d , and it will be understood that the electrical current, in its circuit to a spark-plug (not shown), will jump from a flange a 50 of one eyelet of a pair to an adjacent flange a of said pair, these flanges being nearer together than the flanges b of the pair, this being desired for amplifying or intensifying the electric spark.

55 For the purpose of excluding dust, rain, snow or accumulation of moisture from the

flanges a of the several pairs of eyelets, to prevent short circuits, I provide a casing or housing-box, preferably of rectangular form and of sheet metal, open at its top and bottom, its top having flanges 11 projecting inwardly from its sides, and flanges 12 projecting inwardly from its ends, each end of the casing being incised to provide a pair of 60 prongs 13 and 14.

65 Numeral 15 indicates a transparent plate adapted to engage the inner sides of the flanges 11 and 12, and to be maintained in said engagement by the prongs 14, said prongs being bent inwardly of the ends of 70 the casing to engage the end walls thereof and bent to form projections e for engaging the lower side of the transparent plate 6, and therefore operating as braces, the prongs 13 75 engaging in apertures α and being bent angularly for engaging the ends of the insulating-plate and the outer faces of the ends of the housing-box, and operating as tie-strips for connecting the insulating-plate with the housing-box.

80 According to this construction it will be noted that the housing-box may be very conveniently manufactured, and at a nominal expense; and that, by means of the prongs 13 and 14 the parts may be readily assembled, the insulating-plate being securely held by the prongs 13 as a complete closure for the bottom of the box, and the transparent plate 15 being supported by the prongs 14. 85 Also it will be noted that, by bending the 90 prongs reversely to the direction described, the parts may be readily separated whenever required.

95 As best shown in Fig. 1, one of the eyelets of each pair has a flange a formed non-concentric with its longitudinal axis, and therefore said eyelet may be rotated to dispose said flange farther from or nearer to the flange of the eyelet of the same pair, this being a desirable feature of adjustment, 100 so that the jump-spark may be greater or less, as may be required.

105 While I have described construction in detail, I do not wish to be understood as limiting myself in this respect, and changes in form, size, proportion and minor details may be made, as found to be of advantage, said changes being determined by the scope of the invention as claimed.

110 What I claim as my invention and desire to secure by Letters Patent is,—

1. In combination with a casing incised

- to provide prongs and secondary prongs at its open bottom and to provide flanges projecting inwardly from its open top, a transparent plate within the casing adapted to be engaged by the first named prongs for maintaining it in engagement with said flanges, an insulating-plate having apertures arranged in pairs adjacent to each other and adapted to be engaged by the secondary prongs for maintaining it in engagement with the bottom of said casing, and a plurality of electrodes in the apertures of said insulating-plate.
2. In combination with an elongated, rectangular insulating-plate having apertures arranged in pairs adjacent to each other, metallic eyelets disposed in said apertures and having flanges disposed at the sides of said plate, metallic conductors electrically connected with the eyelets, an elongated, rectangular casing open at its bottom and having flanges projecting inwardly from its open top, a transparent plate within the casing, said casing being provided with prongs for engaging the insulating-plate for securing the latter to the bottom of said casing and having prongs for engaging the transparent plate to dispose said plate in

engagement with the inwardly projecting flanges of said casing.

3. In combination with an insulating-plate having apertures arranged in pairs, the apertures of each pair being disposed at approximately uniform distances from each other, metallic eyelets disposed in said apertures and having circular flanges disposed at the sides of said plate, metallic conductors electrically connected with the eyelets, a casing open at its bottom and having flanges projecting inwardly from its open top, a transparent plate within the casing, said casing being provided with prongs for securing the insulating-plate to the bottom of said casing and having prongs for causing engagement of the transparent plate with the inwardly projecting flanges of the casing, one of the eyelets of each pair being revoluble and having a flange disposed non-concentric with the longitudinal axis of said eyelet.

In testimony whereof, I have affixed my signature in presence of two witnesses.

FRANK G. TOMPSETT.
